UNITED STATES PATENT OFFICE.

FESSENDEN C. BUTTERFIELD, OF MINNEAPOLIS, MINNESOTA, ASSIGNOR OF THREE-FOURTHS TO LOUIS S. CASS, OF SUMNER, IOWA, AND DANIEL B. BURDETT, OF MINNEAPOLIS, MINNESOTA.

FURNACE FOR TREATING REFRACtORY ORES.

SPECIFICATION forming part of Letters Patent No. 518,662, dated April 24, 1894.

Application filed April 24, 1893. Serial No. 471,565. (No model.)

To all whom it may concern:

Be it known that I, FESSENDEN C. BUTTERFIELD, a citizen of the United States, residing at Minneapolis, in the county of Hennepin and State of Minnesota, have invented certain new and useful Improvements in Furnaces for Treating Refractory Ores; and I do hereby declare the following to be a full, clear, and exact description of the invention, such as will enable others skilled in the art to which it appertains to make and use the same.

My invention was especially designed, for use in treating gold and silver bearing ores, but is also applicable to ores containing other kinds of metals.

It is well known, that ores as they come from the mine usually contain many kinds of ingredients. For example, gold and silver bearing ores will often contain sulphur, arsenic, antimony, phosphorus, iron, lead, copper, and other base metals, tellurium, &c.; and these various ingredients are not ordinarily in a free state, but are in combination with other elements, in the form of sulphurates, phosphates, arseniates, antimonates, tellurides, &c. For the past twenty-five years or more, it has been well-known to persons skilled in the art, that one of the most efficient methods of treating such refractory ores, with a view of driving off, by volatilization, such of said elements as are volatilizable at lower temperature than the precious metals, oxidizing such of said metals as are oxidizable under the action of flame, and with a view of reducing the refractory ores containing the precious metals into a suitable condition for milling, amalgamation, and other subsequent steps of treatment, has been to subject the ores to the direct action of an oxidizing flame, in a so-called roasting furnace, and, coincidently therewith, to successively chill the hot ores by intermittently applying thereto either water or a solution of water and salt, or other chemicals.

Various forms of apparatus have been designed and used for carrying out the method of treatment outlined in the foregoing paragraph.

My invention has for its object to provide a furnace or apparatus for carrying out this

old method of treating refractory ores in a more rapid, efficient and economical manner.

To this end, my invention consists in certain novel devices and combinations of devices, which will be hereinafter fully described and be defined in the claims.

My invention is illustrated in the accompanying drawings, wherein, like letters referring to like parts throughout the several views—

Figure 1 is a longitudinal vertical section through my improved furnace, on the line X' X' of Fig. 2, some parts being broken away, and others shown in diagram only. Fig. 2 is an end elevation of the head or receiving end of the furnace, with some of the parts removed. Fig. 3 is a cross section, on the line X² X² of Fig. 1, looking toward the front. Fig. 4 is a cross section, on the line X³ X³ of Fig. 1, looking toward the front. Fig. 5 is an outside view of some of the parts shown in Fig. 2, looking in the direction of the arrow Y, placed near said Fig. 2. Fig. 6 is a detail, partly in elevation and partly in section, of the spraying pipe, used inside the furnace drum, together with a part of its valve mechanism. Fig. 7 is a cross section, on the line X⁴ X⁴ of Fig. 6. Fig. 8 is a detail in section, showing a part of the fuel supply pipe, with modified form of tuyeres. Fig. 9 is a cross section, on the line X⁵ X⁵ of Fig. 8. Fig. 10 is a detail in end elevation, illustrating a device for adjusting the fuel supply pipe and tuyeres. Fig. 11 is a detail in section, illustrating a spraying pipe with rotary instead of sliding valves. Fig. 12 is a cross section of the same, on the line X⁶ X⁶ of Fig. 11. Fig. 13 is a view, partly in front elevation, and partly in diagram, illustrating the valve controlling mechanism, as applied to the rotary valves shown in Figs. 11 and 12. Fig. 14 is a view in diagram, designed to illustrate the relative actions of the rotary drum burner and spraying pipe on the ores.

a represents bed-sills or other fixed structure, upon which the other parts are mounted.

a' is an adjustable platform pivoted at its rear end on the structure a, as shown at a² and securable in any desired vertical adjustment at its forward end, by means of wrench-

60

headed screws a^3 working through nuts a^4 , fixed in the platform a' . The said platform is of metal and preferably composed of longitudinal girders and cross-ties of angle-iron.

5 The platform a' is provided with brackets $a^{3 \frac{1}{2}}$, in which are journaled grooved rollers $a^{4 \frac{1}{2}}$, arranged to form a saddle, for supporting the rotary furnace drum $b b'$, which is provided on its exterior with annular projecting ribs or 10 rings b^2 , resting on the bodies and working between the flanges of said rollers $a^{4 \frac{1}{2}}$. The platform a' also carries bearing brackets a^5 , in which is mounted a worm-shaft c , provided with a driving pulley c' , for the application 15 of power. The worm of the shaft c , engages with an annular worm-gear b^3 on the exterior of the rotary drum $b b'$, for revolving the same. The said rotary drum is composed of an outside metallic shell b and an inside lining b' of fire-clay, fire-brick or other highly refractory material, which is provided with longitudinal corrugations or steps b^4 , on its interior surface.

Rising from the platform a' , at its opposite 20 ends, are pillow-blocks or supports a^6 , in which is journaled a fuel supply pipe d , adapted for the introduction of a fluid fuel, for the production of an oxidizing flame inside the rotary drum. The said fuel supply pipe extends through the drum and is provided with 25 radially projecting tuyeres d' , which are preferably of yoke-like form, as shown in Fig. 1, and are provided with discharge or burner openings d^2 , arranged longitudinally in the 30 drum and below its axis in position to deliver the flames directly onto the ores, under the action of the drum. The burner openings d^2 on the respective tuyeres, are in staggered arrangement, with respect to each other, so 35 as, taken together, to form a continuous sheet of flame. The fuel used would preferably be a highly inflammable gas or vaporized oil heavily charged with oxygen by a forced 40 blast of air or otherwise, so as to produce a powerful oxidizing flame. The radially projecting tuyeres d' , instead of being of the yoke-like form, as shown in Figs. 1 and 3, may be in the form of hollow projecting arms d^3 , as shown in Figs. 8 and 9. The supply pipe 45 d , together with the tuyeres d' , will hereinafter, for convenience, be called the burner. I also desire to note, that I do not confine myself to this form of burner. In a broad point of view, any form of burner located inside 50 the rotary drum, and capable of delivering flames directly onto the ore, under the action of the drum, would be within the scope of my invention. It might be possible, for example, in some classes of ores, to even use a 55 cage for the burner and wood or coal for the fuel, provided only that the cage be so arranged, with respect to its flame openings and its supply of air or oxygen, as to deliver the same directly onto the ore. The burner $d d'$ is angularly adjustable, in its bearings on the pillow-blocks or supports a^6 , for properly 60 directing the delivery of flames from the

tuyeres. Provision may also be made for adjusting the burner toward and from the bearing surface of the drum. This may be 70 readily accomplished, by providing eccentric boxes d^4 , for the ends of the supply pipe d , which may be held in any desired position, by jam-screws d^5 , as shown in Fig. 10. At the same time, the angular adjustment may 75 be readily permitted, by rotating the pipe d in the eccentric-box, and securing the same in any desired position, by set-screws d^6 . If both of these adjustments are to be provided for, eccentric-boxes of this kind would be located in each of the pillow-blocks a^6 . If the eccentric-boxes are or are not used, the angular adjustment of the burner may be readily effected by wrench pins d^7 , at one end of the pipe d , and the same may be held in any 80 desired adjustment, by set-screws d^8 , working through the cap member of either of the bearing boxes.

e is the spraying pipe, journaled as shown in the pillow-blocks a^6 , and extending through the rotary drum and provided with a supply pipe e' , and a waste pipe e^2 . This spraying pipe e is provided with perforated valve-seats e^3 , which as shown, in Figs. 6 and 7, are fitted with sliding valves e^4 attached to a common valve-rod e^5 , normally held in their closed position, by a spring e^6 against a spider-like stop e^7 for the rod, and subject to the action of a valve controller operated either by the drum, as shown, or some other of the constantly 100 moving parts.

As shown, the valve controller consists of a rocker e^8 , journaled in bearings e^9 , projecting from the front pillow-block a^6 , the upper crank-arm e^{10} of which rocker, is connected 105 to the front end of the valve rod e^5 , and the lower crank-arm e^{11} of which rocker, is subject to the action of a trip-lug e^{12} , carried on the front rim of the drum. In virtue of this construction, it is obvious, that at each revolution of the drum, the rocker e^8 will be given an outward throw, thereby sliding the valve-rod e^5 and the valves e^4 against the tension of the spring e^6 and uncovering the perforated valve-seats e^3 .

115 Instead of having sliding valves, as just described, the spraying pipe e may have its perforated valve-seats e^3 fitted with rotary valves e^{13} , carried on a common rotary valve-rod e^{14} , which is operated by a slightly modified form of valve controller. These parts are shown in Figs. 11, 12 and 13. The rocker for the rotary valve, may be a simple bell-crank e^{15} pivoted on a stud e^{16} , projecting inward from the front pillow-block a^6 or carried by some other fixed part, the lower arm of which is in position to be struck by the trip e^{12} on the drum, and the upper arm of which is connected by a buckle equipped rod e^{17} , with a crank-arm e^{18} on the outer end of 120 the valve-rod. The rocker, valve-rod and valves, are held in their normal or closed position of the valves, by a retracting spring e^{19} , applied to the valve-rod arm e^{18} . This spring 125

holds the said arm e^{18} against a fixed stop e^{20} . The buckle on the rod e^{17} permits any desired throw to be given to the rocker e^{15} , under the action of the drum trip e^{12} . This rotary valve construction is preferable to the sliding valves in the spray pipe, for the reason that it permits of any desired rotary movement of the valves e^{18} , and enables the discharge to be graduated, at will, through-
out the entire length of the spray-pipe e . The spray pipe e and its valved discharge openings will be used for introducing the water, with an intermittent action for chilling the ore. It may also be used, for introducing any other liquid solutions or chemicals, such as a solution of salt for chloridizing the ores, or otherwise chemically treating the same.

It will be noted, that the burner tuyeres are in advance of the lowest traverse line of the drum (see Fig. 3), and that the spraying pipe is located between the tuyeres and the lowest traverse line of the drum. This arrangement enables the water or other liquid to be discharged on the ore at the hottest point, and without striking the tuyeres. The spraying pipe has a limited angular adjustment in its bearings, the connections with the valve-rod rocker or controlling device being suitable to permit this movement. The connection, for example, between the sliding rod e^5 and the rocker arm e^{10} (in Fig. 1) may be made by a ball and socket joint e^{21} , and the supply and waste pipes e' and e^2 , may have flexible joints for the same purpose. This adjustment of the spray pipe relative to the tuyeres is desirable, in order to keep the point of discharge from the spray-pipe in the proper position, relative to the tuyeres in their various adjustments.

The receiving end of the drum is fitted and closed by a fixed head b^5 , supported in any suitable way, as for example, from the supply pipe d , and provided with a valved feed-hopper ff' , and a blast inlet pipe g .

The delivery end of the rotary drum is preferably open, as shown in Fig. 1, and connects by a yielding joint $h h'$, with a breeching or hood h^2 , for conducting off the volatilized metals, products of combustion and other gases, to a suitable condenser. As shown, the yielding joint is secured by the grooved rim h , in the groove of which is loosely seated the joint ring h' , which fits the exterior of the drum. The ores, after having been treated in the furnace, are delivered from the drum into an offleading chute k . The furnace is designed for continuous feed from the receiving to the delivery end, the ore being subjected to the heating and chilling actions in its progress from the receiving to the delivery end of the drum. For this purpose, the drum may be tilted on its longitudinal axis, by the construction hitherto described, to give to the same any desired pitch, according to the rate of travel, at which it

may be desired to have the ore move through the drum. As shown, the drum is tapering, being in the form of the frustum of a cone; but it is of course obvious, that it might be a cylinder, and the desired pitch be given by adjusting the receiving end of the platform a' .

An important result, attained by making the drum in the form of the frustum of a cone, is, that the gases on their passage through the drum will be permitted to expand, thus accelerating the travel of the same.

In treating some kinds of ores, it may be desirable to temporarily stop or check the outflow of the ore from the drum; and for this purpose, the breeching h^2 may be provided with a slide-keeper k' , between which and the rim h may be held a slide k^2 , at the delivery end of the drum. For supplying the ore to the feed-hopper ff' , an elevator $f^2 f^3$ may be provided.

The operation is as follows:—The ores are introduced at the head of the drum through the feed-hopper ff' . Supposing the burner to be supplied under pressure with a fuel adapted to produce an oxidizing flame, that the spray pipe is charged with water or other liquid solution under pressure, and that the drum is in motion, and at the proper pitch; then, under the rotation of the drum, the ore will be carried up by the drum until gravity overcomes the centrifugal force, when it will roll back past the tuyeres and through the flames, and at this time, the valves of the spraying device will be moved to deliver onto the ore the spray of water or other liquid solution. The stepped surface of the drum assists in carrying up the ores and is especially serviceable for taking up the fine or powdered material, to a point where, when it rolls back, it will be subjected to the action of the flames, and the water from the sprayer. Under the rotation of the drum, the ore will thus be continuously agitated and heated over and over again to a high degree of heat, which may be regulated to any desired temperature, and will be intermittently chilled by the water or other liquid solution from the spraying device; and, at the same time, it will be worked from the receiving to the delivery end of the drum rendering the action continuous, if so desired. In this way, all the beneficial results of the old and well-known process, outlined in the introductory description, will be secured.

All the volatilizable products, at the given temperature, will be volatilized, the oxidizable materials will be oxidized by the oxidizing flame, and the refractory ingredients will be reduced into a condition suitable for milling and amalgamation, and other subsequent treatments. The volatilized products, as well as the products of combustion will be forced out, by the blast from the pipe g , at the head of the drum into the breeching h^2 , and thence to a condenser and separator, not herein shown.

In the diagram Fig. 14, the roll line of the

ore, under the action of the drum is approximately represented by the arrow-headed line *z*.

For inspection and for the admission of a natural draft to the burners, if desired, the fixed front end *b*⁵ of the drum may be provided with lidded peep holes *b*⁶.

If the slide *k*² be used, at the delivery end of the drum, it may be held in its seat by a sliding lock-bar *k*³, or in any other suitable way.

An efficient method and apparatus for separating out the by-products, which are passed off, in volatile form, from a furnace of the kind herein shown, is disclosed in a companion application, filed by me of even date here-with, Serial No. 471,566, entitled "Method of and apparatus for separating volatilized metals from other commingled gases."

20 My invention has been herein shown and described, as applied for roasting raw ores; but the same apparatus is equally applicable for treating what are known as "concentrates." These "concentrates," as they come 25 from the stamping mill are highly refractory and often contain considerable quantities of the precious metals. By treating the same with my apparatus, these concentrates may be put in condition for free milling.

30 What I claim, and desire to secure by Letters Patent of the United States, is as follows:

1. A furnace for treating refractory ores or similar materials, comprising a rotary drum, arranged for supporting and agitating the 35 ores on its inner surface, and a burner, within the drum and below its axis, for the direct application of flames to the ores, substantially as described.

2. A furnace for treating refractory ores or 40 similar materials, comprising a rotary drum arranged for supporting and agitating the ores on its inner surface and a burner arranged longitudinally in the drum and below its axis for the direct application of flames to the ore, substantially as described.

3. A furnace for treating refractory ores and similar materials, comprising a rotary drum, having its ore-bearing surface inclined downward from its receiving to its delivery end 50 and a burner arranged longitudinally within the drum and below its axis, for the direct application of flames to the ores, whereby, under the rotation of the drum the ores will be agitated and worked from the receiving to 55 the delivery end of the drum, substantially as described.

4. The combination with the rotary drum, of the pivoted platform supporting the drum and provided with means for sustaining it in 60 any desired adjustment, supports fixed upon said platform, and a burner carried by said supports and located within and below the axis of the drum, for the direct application of flame to the ore, and means carried by said platform for supporting and revolving said drum, substantially as described.

5. The combination with the revolving

drum, arranged to support and agitate the ores on its interior surface, of the burner inside the drum consisting of a fuel supply pipe, 70 around which the drum revolves, and tuyeres projecting radially downward from said supply pipe into position to deliver the flames directly upon the ores during the action of said drum, substantially as described. 75

6. The combination with the rotary drum, of the fuel supply pipe around which the drum revolves, provided with radially projecting tuyeres and adjustable in its seat to vary the discharging position of the tuyeres, substantially as described.

7. The combination with the revolving drum, arranged for supporting and agitating the ores on its interior surface, of a burner located within and below the axis of the drum, 85 for the direct application of flames to the ore, and a spraying pipe within the drum for treating the ores with water or liquid solutions, substantially as described.

8. The combination with the revolving 90 drum, arranged for supporting and agitating the ore, on its interior surface, of a burner inside the drum, for the direct application of flame to the ores, a spraying pipe inside the cylinder provided with valved discharge openings and a valve controlling device arranged to be operated by some of the moving parts, with an intermittent action, substantially as described.

9. The combination with the revolving 100 drum, arranged on a downward pitch, for supporting and agitating the ores and working the same from its receiving to its delivery end, of a burner inside the drum, for the direct application of flames to the ores, a spraying pipe inside of the drum, extending the entire length of the same, provided with valved discharge openings spaced apart from each other, and a valve controller arranged to be operated by some of the moving parts, substantially as described. 110

10. The combination with the revolving drum, of the burner inside the drum, for the direct application of flames to the ores, the spraying pipe inside the drum provided with 115 the valved discharge openings, a common valve-rod, under tension, to normally hold the said valves in their closed positions and a valve controller comprising a rocker arranged to be operated by the drum, with an intermittent action, and provided with connections to said valve rod, substantially as described. 120

11. The combination with the rotary drum, of the burner inside the drum, the spraying pipe inside the drum provided with perforated valve seats and rotary valves, normally covering said perforated seats, and connected by a common rod, for uncovering the whole or any part of the discharge openings through said seats, substantially as described. 125

12. The combination with the rotary drum of the burner inside the drum, the spraying pipe inside the drum having perforated valve seats, rotary valves fitting said seats, a com- 130

mon valve rod, a rocker arranged to be intermittently operated by said drum, and a spring applied to hold said valve rod and rocker in their normal position.

5 13. The combination with the rotary drum arranged for supporting and agitating the ore on its interior surface, of the fuel supply pipe inside said drum and longitudinally thereof, provided with radially projecting tuyeres and 10 a spraying pipe with valved discharge openings arranged parallel with and to one side of the tuyeres, substantially as described.

14. The combination with the rotary drum, of the longitudinal fuel supply pipe provided with radially extended tuyeres inside the drum and adjustable into different positions, and the longitudinal spraying pipe provided with valved discharge passages and also adjustable into different positions relative to 20 the tuyeres, substantially as described.

15. The combination with the rotary drum, arranged as described, of the interior fuel supply pipe extending longitudinally of the drum and provided with radially projecting tuyeres 25 set in advance of the lowest traverse of the drum and the spraying pipe with valved discharge openings inside the drum and set to discharge between the tuyeres and the lowest

traverse line of the drum, substantially as and for the purpose set forth.

16. The combination with the rotary drum arranged for supporting and agitating the ore on its interior surface, of the longitudinal fuel supply pipe inside the drum and the pair of yoke-like radial tuyeres projecting from said 35 supply pipe, one in advance of but near to the other, and having their respective discharge or burner openings in staggered arrangement with respect to each other, substantially as and for the purpose set forth.

17. The combination with the rotary drum arranged for supporting and agitating the ores on its interior surface, of a burner inside the drum, for the direct application of flames to the ores, a breeching for conducting off the 45 products of combustion and the volatilized metals and a blast pipe applied to the receiving end of the furnace, above the burner for driving off said gases, substantially as described.

In testimony whereof I affix my signature in presence of two witnesses.

FESSENDEN C. BUTTERFIELD.
